UNITED STATES PATENT OFFICE.

PASQUALE J. BUFFALO, OF MOUNT VERNON, NEW YORK.

MULTIPLE SWITCH.

1,355,002.

Specification of Letters Patent.

Patented Oct. 5, 1920.

Application filed July 5, 1917. Serial No. 178,740.

To all whom it may concern:

Be it known that I, PASQUALE J. BUFFALO, a citizen of the United States, and resident of Mount Vernon, in the county of Westchester and State of New York, have invented certain new and useful Improvements in Multiple Switches, of which the following is a specification.

This invention relates to electric circuit closing devices and has more especial reference to an improved multiple contact switch.

The invention has for its dominant object to provide a switch especially adapted for use in connection with three wire systems whereby two circuits can be closed or opened independently of each other.

Another object of the invention is to provide a switch of the character mentioned which can be used upon winding and reeling apparatus, the switch being provided with a lamp socket in connection with certain of the contacts whereby a lamp can be illuminated and moved to the desired points; the other of the contacts being connected to the motor for rotating or rewinding the reeling apparatus.

The improvements in the details and arrangements of parts will be apparent from an inspection of the accompanying drawings, in connection with the specific description hereinafter contained, wherein the preferred embodiment of the invention is disclosed for the purpose of imparting a full understanding of the invention.

35 In the drawings:

Figure 1 is a vertical section through the improved switch;

Fig. 2 is a side elevation of the improved circuit closing means; and

40 Fig. 3 is a disassembled detail in perspective thereof.

Fig. 4 is a diagrammatic view showing by dotted lines the device, while by full lines there is shown the elements confined therein, the circuits, lamp and external translating device.

Referring more specifically to the drawings, wherein like reference characters designate corresponding parts in the several views, the switch may be stated to include an internally screw threaded socket for receiving an incandescent lamp as indicated by the letter S. A sectional insulating base B is provided and has the socket S secured thereto, while the usual type of insulating protecting hood or casing C is arranged

about the socket and the base, the top thereof being removable and provided with a suitable opening through which conductors c may be passed into engagement with the various contacts of the switch, it of course being understood that certain of the active elements of the switch, hereinafter described, have connection with said socket shell S through the medium of a bolt b.

Seated in suitable seats formed in the base B is a substantially U-shaped contact element 1, the longer end thereof being provided with a laterally offset apertured end through which a screw 2 is passed into engagement with a threaded opening formed in the base; obviously, this screw serving as the binding post or terminal for one of the conductors c. The remaining extremity of the contact 1 is arranged upon the opposite side of the base B adjacent the circuit closing elements 3, one end of which is slightly offset and apertured in order that it can be secured to the base B in a suitable seat formed therein; a second binding post 4 comprising a piece of metal 4 having one end thereof apertured and offset at 5 and the other end also apertured and secured to the base B and engaging the fixed end of the circuit closing element 3 at all times. A screw 6 is passed through the apertured end of the binding post 4 into engagement with the insulated base B to serve as a terminal with which another of the conductors c are engaged.

To facilitate operation of the movable circuit closing element 3 an insulated button 7 having a screw threaded shank is turned into engagement with the free end thereof, and, as shown in Fig. 1, passes through a suitable opening formed in the casing C of the switch. By so connecting the several conductors c it will be appreciated that by depressing the button 7 and causing the contact element 3 to engage the contact element 1 a circuit may be closed therethrough.

As the secondary switch, the ordinary key type of circuit closer is employed and comprises the usual shaft 8 which is journaled in the insulated base B and carries upon one end thereof a cam 9, which cam is arranged adjacent a substantially U-shaped contact member 10 and is adapted to be engaged therewith upon rotation of the shaft 8 by means of the finger piece 11 mounted thereon. A U-shaped metal piece or strip 12 is arranged upon the base B and has its op-

posite ends provided with openings for receiving the ends of the shaft 8 therethrough. Upon this strip 12 a leaf spring 13 is mounted and normally has bearing upon the cam 9. The remaining of the conductors *c* extends into engagement with the strip 12 and, obviously, serves as means for supplying the current thereto in order that a circuit may be closed through the same and through the conductor which is secured to the U-shaped contact element 1 upon the engaging of the cam with the contact element 10; it of course being understood that a lamp or other power receiving element is arranged in the socket *s*. In Fig. 4 of the drawings the electric bulb *L* has its circuit controlled by the switch 9, while the external translating device *M* is controlled by the switch 4.

With my improved multiple contact switch, it will be appreciated by workers in this art that I am enabled to successfully use the same upon various forms of electric translating devices, the switch being especially adapted for receiving and illuminating the ordinary incandescent lamp *L*, the conductors *c* being secured to an electric translating device *M*. By closing the key operated switch 41 the lamp *L* may be illuminated and by depressing the button 7, a second circuit may be closed independently of the lamp circuit, this circuit preferably including the translating device *M*.

Thus, when the lamp has been moved to the desired point and it is then desired to energize the translating device, the circuit controlled by the contact element 3 is closed, thereby energizing the electric translating device.

While I have herein illustrated and described with a considerable degree of particularity constructional details of the device embodying my invention, it is to be understood that the invention is not limited to the particular form and the arrangement of the several parts which may be modified within a wide range without departing from the essence of the invention, the construction shown and the description based thereon being intended to be taken in an illustrative rather than a limiting sense. 50

I claim:—

In combination with an incandescent lamp shell, a multiple point switch including an insulating base, a substantially U-shaped circuit terminal secured to said base 55 and connected to one side of an electrical circuit, a second circuit terminal on the base connected to the opposite side of said circuit, switch means coöperating with said second circuit terminal for closing an electrical circuit through a lamp engaged in the shell and with the first and second mentioned terminals, a resilient contact arm secured to the insulating base adapted to engage with one end of said U-shaped circuit 60 terminal and connected to one side of a second and exterior electrical circuit, said U-shaped circuit terminal serving as a common side for said first and second mentioned electrical circuits, and a finger button connected to the free end of the contact and arranged exteriorly of the shell. 70

In testimony whereof I affix my signature hereto.

PASQUALE J. RUFFALO.
